(57) **CLAIM**

The ornamental design for a pet toy, as shown and described.

DESCRIPTION

FIG. 1 is a front view of a pet toy according to the present disclosure (a back view being identical);

FIG. 2 is a left side view of the pet toy of FIG. 1 (a right side view being identical);

FIG. 3 is a bottom view of the pet toy of FIG. 1 (a top view being duplicative and rotationally offset); and,

FIG. 4 is a perspective view of the pet toy of FIG. 1.

The broken lines shown in the drawings illustrate portions of the pet toy that form no part of the claimed design.

1 Claim, 4 Drawing Sheets
